UNITED STATES PATENT OFFICE.

CHARLES W. PILLARS, OF OTTAWA, KANSAS.

JEWELER'S TOOL.

No. 910,953.

Specification of Letters Patent.

Patented Jan. 26, 1909.

Application filed March 2, 1908. Serial No. 418,843.

To all whom it may concern:

Be it known that I, CHARLES W. PILLARS, a citizen of the United States, residing at Ottawa, in the county of Franklin and State of 5 Kansas, have invented certain new and useful Improvements in Jewelers' Tools, of which the following is a specification, reference being had to the accompanying drawings.

My invention relates to improvements in 10 jewelers' or watch makers' tools and more particularly to a ruby pin setter.

The object of the invention is to provide a tool of this character by means of which a ruby jewel pin may be set without removing 15 the hair spring and roller table from the balance wheel staff, thereby not disturbing the regulation of the watch and not drawing the temper from the staff and pivots of the balance wheel.

With the above and other objects in view, 20 the invention consists of the novel features of construction and the combination and arrangement of parts hereinafter fully described and claimed, and illustrated in the 25 accompanying drawings, in which—

Figure 1 is a perspective view of my improved jewel pin setter; Fig. 2 is an inverted plan view of the same showing a balance wheel in position upon the device; and 30 Fig. 3 is a detail transverse section taken on the plane indicated by the line 3—3 in Fig. 2.

My improved tool comprises two converging resilient or spring jaws 1, 2 having their top faces 3 flat and disposed in the same longitudinal plane and their bottom and inner faces 4 inclined upwardly and inwardly to the top faces 3 so that said blades have their inner portions tapered or beveled to an edge 5 which is V-shaped in cross section, as 35 clearly shown in Fig. 3. The jaws 1, 2 are united at their converging ends to provide a portion 6 adapted to be placed in the flame of a lamp or other heater and upon the opposite end of one of said jaws may be arranged 40 a suitable handle 7 which will enable the tool to be conveniently manipulated and protect the operator's hand from the heat of the jaw. Said jaws 1, 2 are preferably formed from a single piece of copper or other metallic wire 45 by shaping one of its ends to provide the con-

verging upper and lower faces 3, 4 of the jaws and by then bending the portion thus shaped upon itself to provide the end 6.

In use, the balance wheel is placed upon the flat top faces 3 of the jaws and is then 55 moved toward the outer end 6 of the tool so that the inner beveled edges 5 of the jaws will wedge between the roller table and the cross piece of the balance wheel, as clearly shown in Fig. 3. It will be seen that by 60 means of the tool, a roller jewel or ruby pin can be set without removing the hair spring and roller table from the balance wheel staff, thereby not disturbing the regulation of the 65 watch and not drawing the temper from the staff and pivots of the balance wheel staff. The peculiar construction of the tool allows just sufficient heat to be carried from the flame of the lamp to the roller table to melt the shellac with which the ruby pin is fas- 70 tened, thus enabling the workman to set the roller jewel or ruby pin perfectly straight before the shellac becomes cold and sets. By means of the tool, a loose roller jewel or ruby pin may be reset in a few minutes without 75 disturbing the table or hair spring, since the small amount of heat carried by the jaws will not be sufficient to injure said parts.

The tool may be used for slightly annealing the pivots of the balance staff so that they 80 can be straightened without danger of breaking them.

Having thus described my invention what I claim is:

1. A tool of the character described comprising a jaw, a handle at one end of the latter, a second jaw disposed angularly with respect to the first mentioned one, said jaws being united at their converging ends to provide a projection adapted to be heated, the 85 opposing or inner edges of said jaws being beveled, substantially as described.

2. A tool of the character described comprising a handle and a metallic body formed from a piece of resilient wire having one end 95 attached to the handle and its other end bent upon itself to provide converging jaws, said jaws having flat upper faces and inwardly and upwardly inclined bottom faces, said faces providing said jaws with inner edges of 100

V-shape in cross section, substantially as described.

3. A tool of the character described comprising a metallic body formed from a piece 5 of wire by bending the same upon itself to provide the projection 6 adapted to be heated and to provide the converging or angularly disposed jaws 1, 2 having beveled

inner edges and a handle upon the free or diverging end of one of said jaws.

In testimony whereof I hereunto affix my signature in the presence of two witnesses.

CHARLES W. PILLARS.
